US0D1039483S

(12) **United States Design Patent** (10) Patent No.: **US D1,039,483 S**
(45) Date of Patent: ** Aug. 20, 2024

(54) **BATTERY CHARGER**

(71) Applicant: **HUSQVARNA AB**, Huskvarna (SE)

(72) Inventors: **Gustav Landberg**, Trosa (SE); **Tor Sigurdson**, Stockholm (SE); **Patrik Almqvist**, Stockholm (SE)

(73) Assignee: **HUSQVARNA**, Huskvarna (SE)

(**) Term: **15 Years**

(21) Appl. No.: **29/807,994**

(22) Filed: **Sep. 16, 2021**

(30) **Foreign Application Priority Data**

Mar. 18, 2021 (EM) 008465520-0001

(57) **CLAIM**

The ornamental design for a battery charger, as shown and described.

DESCRIPTION

FIG. 1 is a perspective view of a battery charger of the present invention;

FIG. 2 is a front view of the battery charger of FIG. 1;

FIG. 3 is a rear view of the battery charger of FIG. 1;

FIG. 4 is a left side view of the battery charger of FIG. 1;

FIG. 5 is a right side view of the battery charger of FIG. 1;

FIG. 6 is a top view of the battery charger of FIG. 1; and,

FIG. 7 is a bottom view of the battery charger of FIG. 1.

The broken lines of FIGS. 1-7 form no part of the claimed design.

1 Claim, 7 Drawing Sheets
